CONTAINER FOR PIZZA OR THE LIKE

George E. Meyer, 217 S. Knott, Anaheim, Calif. 92804

Filed May 17, 1971, Ser. No. 144,353

Term of patent 7 years

Int. Cl. D9—03

U.S. Cl. D9—237

Fig. 1

Fig. 2

FIG. 1 is an exploded perspective view of a container for pizza or the like showing my new design;

FIG. 2 is a side elevation view on a reduced scale with the lid in place; and

FIG. 3 is a bottom perspective view of the lid on the same scale as FIG. 2.

I claim:

The ornamental design for a container for pizza or the like, as shown.
